UNITED STATES PATENT OFFICE.

HORACE S. BLINN, OF OMAHA, NEBRASKA.

DEPILATING COMPOUND.

SPECIFICATION forming part of Letters Patent No. 707,953, dated August 26, 1902.

Application filed October 17, 1901. Serial No. 79,010. (No specimens.)

To all whom it may concern:

Be it known that I, HORACE S. BLINN, a citizen of the United States, residing at Omaha, in the county of Douglas, State of Nebraska, 5 have invented or discovered a new and useful Improvement in Depilating Compounds, of which the following is a specification.

My invention or discovery relates to depilating compounds; and the object thereof is to 10 provide a compound for removing superfluous growths of hair from the human body and to kill the roots to prevent subsequent growth of hair, but without injuring the skin.

My compound consists of calcium oxide or 15 quicklime in the proportion varying from eighty to ninety-two parts, mixed, preferably, with equal quantities of arsenic disulfid (As_2S_2) and arsenic trisulfid (As_2S_3) to form the remaining twenty to eight parts—that is 20 to say, the arsenic sulfid employed consists, preferably, of about equal quantities of disulfid and trisulfid, while the lime preferably forms eighty to ninety-two parts of the compound. To permanently kill the hair follicles or roots, powdered hyposulfite of soda is 25 added to the ingredients just mentioned in such quantity as to form about ten percent. of the entire compound. By preference a perfume, such as orris-root, will be employed to 30 deaden the odor of the compound. This ingredient, however, is not essential and is without effect upon the skin.

The method of using the above-described compound is to make a paste by mixing the calcium oxide and arsenic sulfid with water, and this paste is then spread over the surface from which the hair is to be removed. After the lapse of from ten to forty minutes the paste 35 may be removed by scraping the skin with a smooth blunt instrument, as a bone or wooden spatula, when the hair will come off with the paste. The surface of the skin is then cleansed thoroughly with pure water without 40

the use of soap and subsequently dried. When used in this manner, the hair will be 45 completely removed without harm to the most delicate skin.

When a compound is desired which will 50 permanently kill the hair roots or follicles, powdered hyposulfite of soda is added to the calcium oxide and arsenic sulfid in such quantity as to form, preferably, about ten per centum of the entire compound. The method 55 of using this compound, comprising hyposulfite of soda, is the same as above described; but the application should be repeated two or three times weekly, the strength of the hair becoming less and less after each application. After a series of applications the hair ceases 60 to grow, the necessary number of applications varying with the strength of the growth of hair. The skin instead of being discolored or otherwise harmed by the use of my compound is rather softened and tends to become 65 whiter and clearer than previous to the application.

What I claim as new, and desire to secure by Letters Patent, is—

1. The herein-described composition of matter for removing superfluous human hair and 70 preventing the subsequent growth thereof, the same consisting of calcium oxide or quicklime, arsenic sulfid and hyposulfite of soda, in substantially the proportions stated.

2. The herein-described composition of matter for removing human hair and preventing 75 the subsequent growth thereof, the same consisting of about eighty to ninety-two parts calcium oxide, eight to twenty parts of arsenic sulfid and ten parts sulfite of soda mixed with 80 water to form a thick paste.

HORACE S. BLINN.
